COMBINED MOUNTING CASE AND HOLDER FOR SAFETY RAZOR

Abram W. Smith, 1826 Virginia Road,
Los Angeles, Calif. 90019

Filed Oct. 18, 1965, Ser. No. 87,559

Term of patent 14 years

(Cl. D4—3)

FIG. 1.

FIG. 2.

FIG. 3.

FIG. 4.

FIGURE 1 is a front perspective view of a combined mounting case and holder for safety razor, showing my new design;

FIGURE 3 is a perspective view thereof, the case door being opened to show the holder for a safety razor; and,

The razor and package shown in broken lines in FIG. 3 are included for illustrative purposes only.

I claim:

The ornamental design for a combined mounting case and holder for safety razor, substantially as shown and described.
